UNITED STATES PATENT OFFICE.

GOTTLIEB I. STASTNY, OF NEW YORK, N. Y.

ROTARY COMPRESSOR.

Application filed February 5, 1927. Serial No. 166,064.

The main object of this invention is to provide a rotary compressor having a number of novel characteristics among which an automatic means is provided diverting the air in the compressor into the atmosphere when the pressure in the receiver tank has arrived at a certain predetermined level, thereby making the machine absolutely safe in operation.

Another object of the invention is to provide a compressor unit which is operated automatically in conjunction with a storage tank and has for one of its essentials the provision of a valve which gradually opens or closes as the contents of the storage tank arrives at a predetermined but not necessarily full pressure. The valve is of novel design situated midway the length of the circular path which the rotor describes in the compression chamber and opens or closes ports, gradually and partly or wholly, being actuated by a plunger on which the pressure of the contents of the tank is projected. The valve permits a portion of the air drawn into the compression chamber to be exhausted into the atmosphere, that portion of the air passed into the atmosphere not being necessary to retain the pressure in the tank up to a suitable working level.

The above and other objects will become apparent in the description below in which characters of reference refer to like-named parts in the drawing.

Referring briefly to the drawing, Figure 1 is a vertical sectional side elevational view of the compressor showing the valves and rotor in detail.

Figure 2 is a longitudinal sectional elevational view of the compressor unit, the section being taken lengthwise along the shafts of the device.

Figure 3 is a top plan view of the compressor with the pop valve and pop valve housing removed to show the structure of the compressor in greater detail.

Referring in detail to the drawing, the numeral 10 indicates a substantially cylindrical casing which is formed integral and houses the compressor rotor. This casing has a pair of flanges which extend diametrically outward in opposite directions and are indicated by the numerals 11 and 12. Within the casing a precise annular chamber 13 is formed which is bounded by a peripheral wall 14. A sleeve 15 is formed on one side of the casing and the axis of this

sleeve is offset upwardly and vertically and at an angle to the axis of the chamber 13. This sleeve has an opening 18 therein communicating with the chamber 13 and has a pair of external raceways 16 and 17 mounted therein spaced apart from each other. A spindle 21 has a pair of raceways 19 and 20 mounted thereon and is rotatably mounted in the sleeve 15. To eliminate friction as much as possible the raceways 16 and 17 are separated from the raceways 19 and 20 and in the space between the pairs of raceways rollers 22 are positioned and form roller bearings for smooth running of the spindle. The outer end of the sleeve 15 is open and is sealed by a cover 23 which is secured in place by screws 24 which latter thread into the wall of the sleeve and detachably secure the plate in place so that it may be easily removed. The end of the spindle which projects into a recess 25 positioned between the chamber 13 in the casing and the opening 18 in the sleeve has a flange 26 formed on that end, said flange being rotatable in the recess and carries a relatively large drum 27 which forms the rotor of the compressor. The drum is mounted detachably on the flange and is secured to the latter by bolts 28 which have their heads counterbored into the flange. As the axis of the spindle 21 is off-set from the axis of the compartment or chamber 13 in the casing 10 and the drum 27 being positioned in the chamber 13 the drum will consequently be rotatable in the chamber 13 in an eccentric position. The drum is of hollow construction, having an annular space 29.

One face of the casing is open and is closed and sealed by a flanged cap 30 which is secured in place by bolts 31 which thread into the face of the casing surrounding the opening in the face. Said cap is provided with an opening in which the threaded end 32 of a shaft 33 is secured by nuts 34. The shaft 33 has a stop flange 35 provided thereon which seats on the surface of the cap. Said flange projects inwardly into the chamber 13 formed in the casing 10 and axially positioned therein. This shaft is rigidly mounted in place and does not rotate. A collar 36 is rigidly mounted on the shaft 33 and serves as a bearing upon which a pair of blades 37 and 38 are loosely mounted and are consequently in a position to swing around the axis of the shaft 33. The blades are L-shaped and are provided

with tongues which have a thickness of half the depth of the chamber 13 so that the tongues of both blades when put side by side will extend thru the entire depth of the chamber 13 as is illustrated in the Figure 2. The tongues 39 of these blades are semi-circular in cross section so that that portion on one side of the center will be counterbalanced by the weight of the blade on the opposite side, as is indicated in Figure 1. The blades radiate from the center to the peripheral wall of the chamber in substantially diametrically opposed directions and at their free extremities are provided with channels 40 which extend the entire length of the blades. At the ends of these channels 40 intersecting and similar channels are formed on the sides of the blades. The longitudinal channels 40 harbor cushion blocks 41 which are slidably mounted therein and the channels formed on the sides of the blades are adapted to receive shorter blocks 42 which are shorter than the first-mentioned blocks. At the position where the blocks 41 and 42 intersect they are mitered to a 45 degree angle so that the blocks 42 form a leak-proof fit with the blocks 41 as is indicated in Figure 2. Openings 43 are formed in the blades at right angles to the blocks 42 and house compression springs 44 which are adapted to normally urge said blocks 42 outwardly into contact with the faces of the chamber 13 so that a leak-proof fit is obtained. At substantially diametrically opposite positions on the rim 45 of the drum 27 circular passageways are formed which extend thru the width of the drum and have substantially semi-circular guides 46 riding therein. These guides are arranged in pairs with the blades 37 and 38 movable between them the blades being free to slide between them.

A curved and semi-circular passageway has its mouth open to the atmosphere exterior of the casing and communicates at its opposite end with the chamber 13 in the compressor casing the entrance being indicated by the numeral 48. At the point of entrance into the chamber of the entrance of the passageway V-shaped ridges 49 are formed which form substantially triangular channels 50 thru which the incoming air rushes in jets.

The wall separating the passageway from the channel 47 is flat at its upper portion and has an annular recess formed therein in which recess a disk 51 is seated. Said disk is securely attached to an inverted bell 52 which is let into the chamber above and communicating with the passageway 47 at a position intermediate its length. The wall 53 bounding the passageway 47 at the top thereof has a pair of semi-circular oppositely disposed channels 54 formed therein thru which the compressed air escapes from the compression chamber 13. The disk 51 has similar

and aligned channels 55 which form a line of communication with the first-named channels 54. On its upper face the disk has two spaced apart upstanding ridges between which the channels 55 in the disk emerge 70 into a compartment 56 in the bell 52. The ridges on the disk form a seat for a flange 57 which is provided with a vertically positioned hub 58 which is slidably mounted on a guide 59 whose head 61 is embedded in a recess formed axially in the disk 51. At the intersection of the flange 57 and the hub 58 an angular wall is provided in which ports 60 are formed which serve as additional outlets for the compressed air when the disk 55 is in raised position above and lifted from the ridges formed on the disk 51. The upper end 62 of the guide bolt 59 is threaded and engages a nut 63 which holds a stop washer 64 in place on the guide bolt seated 85 on a sleeve 66. The washer retains a spring 65 in position wound around the guide bolt, said spring being adapted to yieldably urge the disk 57 downwardly into seating contact on the ridges formed on member 51. The inverted bell 52 is provided with a flange 67 which is supported on the casing 10 and is secured in place by bolts 68. The bell has a curved mouth 69 extending therefrom above the flange which has a pipe line 70 95 coupled thereto which latter leads to the compressed air tank (not shown on the drawing) which may be situated at any desirable position.

Beside the bell a T-shaped fixture 71 is mounted on the casing. This fixture has a hollow stem 72 in which a plunger 73 is slideable. The latter named plunger has a downwardly extending shank 74 secured thereto and at the lower end of the shank 105 a valve head 75 having an angular periphery is formed. The periphery of this valve normally seats on the lower corner of the stem and is urged into this closed position by a spring 76 which is coiled around the stud 110 77 and is located beneath the valve head in a chamber 78 which latter communicates with the curved channels 54 and 55 formed above the casing. An annular opening 79 forming an outlet port is formed in the stem 115 of the T-shaped fixture and forms a lane of communication between the curved channels 54 and 55 and the atmosphere thru which the air may escape when the valve head is lowered from its seat on the lower end of the stem. The upper horizontal arm 80 has a bore extending thru its entire length and is threaded at one end, the latter end receiving a hollow bored bolt 81 whose bore has one end of a spring 82 inserted therein. A piston 84 is slideable in a restricted portion of the bore 83 in the horizontal arm of member 71. This piston has one end provided with a flange 85 which forms a stop for the expansion spring 82, the latter en- 120 125 130 135

gaging and seating on said flange for normally urging said piston toward the end of member 80 to which the pipe 86 is attached. Intermediate the length of the piston an annular groove 87 is formed on said piston. A bore is formed in the piston and extends from a point midway of its length to the end of the piston opposite to the flange 85. The bore in the piston is shown by dotted lines in Figure 1 and it communicates with the groove 87 thru the plurality of ports 88 formed radially in the piston. A passage 89 connects the bore 88 with the upper end of the chamber provided in the vertical part of member 71 so that any air that enters the bore of the piston will pass thru the passage 89 and enter into the chamber providing the groove 87 in the piston is aligned with the passage 89. The pipe 86 extends to the reservoir of the tank in which the supply is kept and may be positioned at any point remote from the compressor, said tank not being shown in the drawing. This pipe 86 leads a stream of air into the compressor control mechanism and acts on the valve head 75 when it is desired to pass the compressed air into the atmosphere.

A volume air intake control mechanism is provided on the compressor and measures and controls the amount of air drawn into the chamber 13 of the compressor member 10. The wall 90 of the casing 10 of the compressor is deformed to provide an annular well 91 in which a cage 92 is secured by bolts 93. This cage is closed at its outer end by a face 94 in which an axial opening is formed. The cage extends horizontally into the well and rotatably secures an annular closure disk 95 in place in the bottom of the well in contact with the face of the wall 96 provided in the bottom of the well. The wall at the bottom of the well is provided with a pair of elongated ports 97 which pass entirely thru the well and are adapted to align with similar ports 98 formed in the closure disk 95 when the latter is rotated to one position. The disk 95 has an axial stud or shaft 99 extending therefrom which passes thru the opening provided in the well in the portion 94. The stud has a crank arm 100 secured thereto which is provided with a slotted end. The slotted end of the crank arm 100 is engaged by a rod 101, the latter having a plunger 102 secured to its end which is reciprocal in a shell 103. Said shell has a cap secured to its lower end and beneath the plunger a coil spring 104 is wound about the rod seats on said cap and normally lifts the plunger upwardly. The compressor illustrated in the drawing is adapted to furnish compressed air to a tank situated at some position remote from the compressor but connected thereto by pipe line 70, said storage tank not being shown on the drawing. The spindle 21 is rotated by

some source of power, not shown on the drawing. As the spindle is connected to the drum 27, the latter is also rotated. The axis of the spindle is off-set vertically and at an angle to a shaft 33 which is rigid and non-rotatable and serves as a support for a pair of blades 37 and 38 which are positioned in slots in the drum and thru this interlocking are caused to rotate within the annular chamber 13 whose center is on the axis of the shaft 33. The drum rotates on a raised axis and is of smaller dimensions than the annular chamber 13 thus forming a crescent shaped space which is divided in two by the blades. As the lowermost blade 38 sweeps around on its travel the air in that portion of the space in front of it is urged into the curved channels 54. This air driven into the channels 54 is compressed and raises the flange 57 from its seat and captures this air in the bell 52. The air flows from the latter into the storage tank thru the pipe line 70.

When the pressure in the storage tank has reached a predetermined limit it backs up thru the pipe 86 and acts upon a piston 84 urging the latter away from the pipe against the tension of the spring 85 thereby aligning the channel 87 and the ports 88 formed in said piston with the opening 89 which latter communicates with a sealed chamber in which a plunger 73 is slidable. The valve 75 rigid with the plunger 73 is lowered from its seat and opens the passage-way 47 to the atmosphere thru the port 79 thus diverting the air stream which circulates from the chamber 13 from the storage tank. This cut-off means begins to operate automatically immediately upon the storage tank arriving at a predetermined pressure.

Another pipe line from the storage tank is connected to the pipe line and member 103, particularly to the upper end of latter and when the piston 102 is depressed by the pressure in the storage tank the disk 95 is rotated until the ports 98 in the disk are either partly or wholly aligned with the ports 97 in the floor of the well after which a portion of the air drawn into the crescent-shaped chamber is passed into the atmosphere and when these ports are aligned the compressor is not operating at a maximum load.

It is to be noted that certain changes in form and construction may be made without departing from the spirit and scope of the invention.

I claim:

1. In a compressor, a casing having a cylindrical chamber therein, an annular drum rotatable in said chamber eccentrically, said drum having opposing diametral channels therein, counter balanced blades slidable in said channels and rotatable with the drum, a bell above said casing, curved chan-

nels connecting said bell and chamber, a check valve in said bell opening or closing communication to said curved channels; a valve normally closing said curved channels, and means for by-passing the air stream from the curved channels into the atmosphere.

2. In a compressor, a casing having a cylindrical chamber therein, an annular drum mounted in said chamber eccentrically, said drum having channels extending diametrically, a shaft projecting axially into said chamber and into said drum, a pair of opposing blades rotatably mounted on said shaft slideable in said drum channels and rotatable with the drum, a passageway in said casing above said chamber and communicating with the latter thru curved channels, a check valve normally closing one end of the curved channels, a valve in said passageway normally closing an opening into the atmosphere, and means for opening said valve when the air compressed rises above a predetermined pressure.

3. In a compressor, a casing having a cylindrical chamber, an annular hollow drum rotatable in said chamber eccentrically, said drum contacting with the wall of said chamber beside the upper dead center, said drum having substantially opposing diametral channels therein, counterbalancing blades slideable in said channels and rotatably guided by said drum, said blades having channels therein formed on the edges of said blades which contact with the surface bounding said chamber, blocks in said channels of said blades, an inverted bell above said casing, curved channels connecting said bell and chamber, a vertically movable check valve in said bell normally covering said curved channels, and valve operated means for by-passing the air stream from the curved channels into the atmosphere.

4. In a compressor, a casing having a cylindrical chamber, an annular hollow drum rotatable in said chamber eccentrically, said drum contacting with the wall of said chamber beside the upper dead center, said drum having substantially opposing diametral channels therein, counterbalancing blades slideable in said channels and rotatably guided by said drum, said blades having channels therein formed on the edges of

said blades which contact with the surface bounding said chamber, blocks in said channels of said blades, said blocks mounted in said channels formed at the contacting edges thereof having tapering ends, said blades having additional channels formed at the sides, said channels being mutually parallel, blocks in said parallel channels, resilient means urging said blocks in said parallel channels into contact with the side surfaces bounding said chamber, an inverted bell above said casing, curved channels connecting said bell and chamber, a vertically movable check valve in said bell normally covering said curved channels, and valve operated means for by-passing the air stream from the curved channels into the atmosphere. 70

5. In a compressor, a casing having a cylindrical chamber, an annular hollow drum rotatable in said chamber eccentrically, said drum contacting with the wall of said chamber beside the upper dead center, said drum having substantially opposing diametral channels therein, counterbalancing blades slideable in said channels and rotatably guided by said drum, said blades having channels therein formed on the edges of said blades which contact with the surface bounding said chamber, blocks in said channels of said blades, said blocks mounted in said channels formed at the contacting edges thereof having tapering ends, said blades having additional channels formed at the sides, said channels being mutually parallel, blocks in said parallel channels, coiled springs mounted in said blades beneath said parallel channels, said springs resiliently urging said blocks in said parallel channels outwardly to contact with the side surfaces of the chamber, the blocks in said parallel channels contacting with the blocks in the end channels being inclined so as perfectly 95 form a corner by said intersecting blocks, an inverted bell above said casing, curved channels connecting said bell and chamber, a vertically movable check valve in said bell normally covering said curved channels, and valve operated means for by-passing the air stream from the curved channels into the atmosphere. 100

In testimony whereof I affix my signature.

GOTTLIEB I. STASTNY.
